UNITED STATES PATENT OFFICE.

WILLIAM F. WRIGHT, OF CHESTER, PENNSYLVANIA.

HOT-METAL DISPATCHER.

Application filed December 31, 1921. Serial No. 526,249.

To all whom it may concern:

Be it known that I, WILLIAM F. WRIGHT, a citizen of the United States, residing at Chester, in the county of Delaware and 5 State of Pennsylvania, have invented new and useful Improvements in Hot-Metal Dispatchers, of which the following is a specification.

This invention relates to hot metal dispatchers and it has more particular reference to pneumatic rivet passing apparatus or devices, the primary object being to provide a means which will allow for the dispatch of a heated rivet from the point where 10 it is heated to a remote or distant location; in other words, that is the locating of the heating apparatus and the dispatcher in the open for example and dispatching the heated rivet to a remote point such as the interior of a ship's hull in order to eliminate 15 gases in said hull, that would necessarily be caused by having the heating of the rivet therein. Furthermore my improved rivet passing apparatus eliminates the use of manual passers and delivers the heated rivets to the place where they are to be used in a 20 properly heated and good condition.

A further object of this invention is to 25 provide a rivet passing device of the foregoing specified character that is simple in construction, and efficient in operation.

With the foregoing and other objects in view as will be more clearly apparent from the following description my invention consists essentially of a tank or chamber which 35 forms a standard for the device, and in this tank there is provided a compressed air chamber, the operating mechanism being also concealed within the aforesaid tank. 40 Suitably supported by the tank is a despatching chamber which is in communication with the compressed air chamber and under the control of a valve normally held closed and operable by the mechanism contained within 45 the tank, said mechanism being conveniently manually actuated by means of a foot treadle or the like. The despatching chamber for the rivet is provided with an opening normally closed by a flap valve, and 50 through this opening the rivet is inserted into said despatching chamber whence it falls by gravity into a discharge outlet and travels through a helical metal tube or the like to the point where it is to be used under the action of the compressed air liberated 55 from the compressed air chamber when the

valve controlling its discharge is tripped or manually opened.

In the further disclosure of the invention reference is to be had to the accompanying 60 sheet of explanatory drawings constituting a part of this specification and in which like characters of reference designate the same or corresponding parts in both the views.

Figure 1 is a top plan view of my improved rivet passing apparatus; and, 65

Figure 2 is a vertical section taken substantially on the line 2—2 in the preceding figure.

Referring to the drawings the numeral 3 70 designates a conical tank which provides a support for and is in communication with a dispatching chamber 4 into which the rivet is placed and from which the rivet is dispatched through a metal tube 5 to the de- 75 sired point, the tank 3 containing the compressed air which is used to impel the rivet through said metal tube 5. The conical tank 3 is closed at its lower end by a flanged base plate 6 to form a base for the device. 7 des- 80 ignates a flanged partition spaced from the base plate 6 and secured at its flanged portion to the walls of the tank 3 the space be- 85 tween the said partition 7 and the base plate 6 forming a compartment for enclosing cer- 90 tain of the operating mechanisms to be hereinafter referred to. The upper end of the tank is closed by a cap plate 8 engaging an inwardly extending flange 9 on the tank 5, this cap plate 8 is secured to the flange 9 by 95 any desirable fastening means such as the bolt and nut connection—as shown. Packing may be inserted between the cap plate 8 and the flange 9 to prevent leakage of compressed air. The space between the cap plate 8 and the partition 7 forms a com- 100 pressed air chamber 10 having an inlet 11 communicating with a convenient source of supply of compressed air. The cap plate 8 and the partition 7 have central threaded openings 12, 13 respectively and into the opening 12 is threaded a flanged nipple 14, the flanged portion engaging the upper face of said plate 8 while the lower portion there- 105 of is provided with a conical seat for the valve 15 which is provided with fingers 16 guided in the nipple 14, the space between said fingers 16 allowing for the passage of compressed air when the valve is in the open position. This valve 15 is provided with a 110 depending annular portion 17 forming a socket in which is positioned the head 18 of

a valve rod 19, said head 18 being retained in the socket by a cap 20 having a central opening for the passage therethrough of said valve rod. The socket 17 being slightly larger in a vertical direction than the head 18 of the valve rod 19 allows for a retardation in the opening of the valve when the rod 19 is actuated. 21 designates a stuffing box threaded into the threaded opening 13 of the partition 7, said stuffing box 21 having a central opening through which the valve rod 19 passes. 22 designates a central vertical guide sleeve carried by the partition 7 through which the rod 19 passes and is guided. 23 designates packing held in the stuffing box to surround the rod 19 and prevent leakage of air past the gland 24 which is held on said packing 23 by the nut 25 threaded into the lower portion of the stuffing box 21. 26 designates a coiled spring seated on a washer 27 supported on the upper portion of the sleeve 22, the other end of said spring 26 engaging against a collar 28 fixed to the rod 19 and thereby exerting an upward pressure which holds the valve 15 supported by the rod 19 in a normally closed position with respect to its seat against the flanged nipple 14. The lowermost end of the rod 19 is provided with a bifurcated portion 28 straddling and pivoted at 29 to a treadle lever 30 which is fulcrumed to a bracket 31 depending from and secured beneath the partition 7, whilst the free end of the treadle extends through an opening 32 in the wall of the tank 3 where it is provided with a foot piece 33. 34 designates a set screw threaded into a bracket 35 located below the treadle lever 30, and said set screw 34 is provided with a lock nut 36 for adjustment to limit the downward movement of the treadle lever 30 and thereby control the lift of the valve 15 with respect to the pressure of the compressed air in the operation of the apparatus.

45 A tubular member or pipe 37 is screwed into the flanged nipple 14 and on the upper end of said tubular member 37 is suitably attached the aforesaid dispatching chamber 4. The upper open portion of the dispatching chamber 4 is closed by a cap plate or cover 38 having a receiving opening 39 for the insertion of a rivet into said dispatching chamber. The receiving opening 39 is normally held closed by an upwardly acting flap valve 40 seating against the conical seat 41 of the cap plate 38. This flap valve 40 is pivoted at 42 to the underside of the cap plate 38 and it is provided with an integral bell crank counter-balance 43 which normally tends to hold said valve 40 in a closed position with respect to the receiving opening 39.

The receiving opening 39 for the rivet is out of alignment with the opening in the tubular member or pipe 37 to prevent a

70 rivet when passed therethrough from falling into said tubular member or pipe 37. The dispatching chamber 4 is provided with an outwardly and downwardly depending integral enlargement 44, said enlargement having an opening which communicates into the dispatching chamber 4, said opening being also in communication with the helical metal tube 5 ferruled thereon at 45 and held with respect to the enlargement 44 by a nut 75 46 threaded into a threaded opening in said enlargement.

75 Referring to Figure 2 it will be clearly seen that the outlet from the valve dispatching chamber is disposed angularly with respect to the rivet receiving opening 39 and is substantially in alignment under the said opening 39 thereby facilitating the passage of a rivet into the tube 5. The use of a helical metal tube 5 effects the thorough cleaning of the rivet from scale in its passage therethrough, the action thereof being similar to a rotatable barrel for cleaning scale from metal parts. It will of course be understood that the free end of the tube 5 is 90 provided with a rivet receiver—not shown on the drawings.

95 In the use of the apparatus the same may be located at a distance from the place where the riveting is to be done, that is to say the device may be located in the open and the rivets passed thereby to a confined space such as the hull of a ship where it is desirable to eliminate the gases caused by the heating of rivets. In the operation of the 100 apparatus a hose communicating with a source of supply of compressed air is coupled to the inlet 11 to supply compressed air into the compressed air compartment 10. After the rivet is heated the operator inserts the 105 same into the receiving opening 39, and said rivet by its own weight will cause the flap valve 40 to open and allow said rivet to fall into the dispatching chamber 4, and thence into the metal tube 5. The flap valve 110 40 then automatically closes under the action of its weighted extension or counter-balance 43 which as before stated tends to hold the valve in a normally closed position. The operator presses his foot on the foot 115 piece 33 which rocks the treadle 30 downwards and causes the valve rod 19 pivoted thereto to be moved downward in opposition to the action of the spring 26. This downward movement of the rod 19 causes 120 the valve 15 to move away from its seat and thereby allowing the compressed air in the compartment 10 to pass through the nipple 14, tube or pipe 37 into the dispatching chamber 4, said compressed air impelling the 125 rivet through the tube 5 to the receiver and from which receiver and rivet is taken to be used as and where desired.

130 From the foregoing description it will be clearly apparent that by my invention there

is provided an extremely effective apparatus for the purposes specified, and whilst there has been illustrated one practical embodiment thereof the same is not to be conservatively construed as it will be obvious many detail changes may be evolved without departing from the spirit and scope of the invention; the right is therefore hereby reserved to make such changes and modifications as fairly lie within the scope of the appended claims.

Having described my invention, what I claim as new and desire to secure by Letters Patent is:

- 15 1. A rivet dispatching apparatus comprising a frustoconical tank having a transverse partition providing superposed compartments the upper of which is adapted to contain compressed air, a rivet dispatching 70 chamber mounted above and having tubular connection with the compressed air compartment, a conduit leading from said rivet dispatching chamber, an upwardly seating spring influenced valve having guiding fingers 75 slidable in the lower end of the tubular connection, said valve normally closing communication between the compressed air and rivet dispatching chambers, a hot rivet receiving opening in the top of the dispatching chamber, a counterbalanced upwardly seating pivoted valve normally closing the rivet receiving opening, the aforesaid conduit being disposed below and outwardly inclined relative to the receiving opening, and means for opening communication between the compressed air chamber and rivet dispatching chamber to impel the rivet through 80 the aforesaid conduit.
- 20 2. A rivet dispatching apparatus comprising a frusto-conical tank having a transverse partition providing superposed compartments the upper of which is adapted to contain compressed air, a rivet dispatching 85 chamber mounted above and having tubular connection with the compressed air compartment, a conduit leading from said rivet dispatching chamber, an upwardly seating 90 spring influenced valve having guiding fingers slidable in the lower end of the tubular connection, said valve normally closing communication between the compressed air and rivet dispatching chambers, a hot rivet 95 receiving opening in the top of the dispatching chamber, a counterbalanced upwardly seating pivoted valve normally closing the rivet receiving opening, the aforesaid conduit being disposed below and outwardly inclined relative to the receiving opening, and means for opening communication between the compressed air chamber and rivet dispatching chamber to impel the rivet through 100 the aforesaid conduit.
- 25 3. A rivet dispatching apparatus comprising a frustoconical tank having a transverse partition providing superposed compartments the upper of which is adapted to contain compressed air, a rivet dispatching 105 chamber mounted above and having tubular connection with the compressed air compartment, a conduit leading from said rivet dispatching chamber, an upwardly seating 110 spring influenced valve having guiding fingers slidable in the lower end of the tubular connection, said valve normally closing communication between the compressed air and rivet dispatching chambers, a hot rivet receiving opening in the top of the dispatching chamber, a counterbalanced upwardly seating pivoted valve normally closing the rivet receiving opening, the aforesaid conduit being disposed below and outwardly inclined relative to the receiving opening, and means for opening communication between the compressed air chamber and rivet dispatching chamber to impel the rivet through 115 the aforesaid conduit.
- 30 4. A rivet dispatching apparatus comprising a frusto-conical tank having a transverse partition providing superposed compartments the upper of which is adapted to contain compressed air, a rivet dispatching 120 chamber mounted above and having tubular connection with the compressed air compartment, a conduit leading from said rivet dispatching chamber, an upwardly seating 125 spring influenced valve having guiding fingers slidable in the lower end of the tubular connection, said valve normally closing communication between the compressed air and rivet dispatching chambers, a hot rivet receiving opening in the top of the dispatching chamber, a counterbalanced upwardly seating pivoted valve normally closing the rivet receiving opening, the aforesaid conduit being disposed below and outwardly inclined relative to the receiving opening, and means for opening communication between the compressed air chamber and rivet dispatching chamber to impel the rivet through 130 the aforesaid conduit.
- 35 5. A rivet dispatching apparatus comprising a frusto-conical tank having a transverse partition providing superposed compartments the upper of which is adapted to contain compressed air, a rivet dispatching chamber mounted above and having tubular connection with the compressed air compartment, a conduit leading from said rivet dispatching chamber, an upwardly seating spring influenced valve having guiding fingers slidable in the lower end of the tubular connection, said valve normally closing communication between the compressed air and rivet dispatching chambers, a hot rivet receiving opening in the top of the dispatching chamber, a counterbalanced upwardly seating pivoted valve normally closing the rivet receiving opening, the aforesaid conduit being disposed below and outwardly inclined relative to the receiving opening, and means for opening communication between the compressed air chamber and rivet dispatching chamber to impel the rivet through the aforesaid conduit.

fluenced valve and having pivotal connection with a foot lever fulcrumed below the transverse partition whereby said valve is opened to impel the hot rivet through the aforesaid conduit.

6. A rivet dispatching apparatus comprising a frustoconical tank having a transverse partition providing superposed compartments the upper of which is adapted to 10 contain compressed air, a rivet dispatching chamber mounted above and having tubular connection with the compressed air compartment, a conduit leading from said rivet dispatching chamber, an upwardly seating 15 spring influenced valve having guiding fingers slidable in the lower end of the tubular connection, said valve normally closing communication between the compressed air and rivet dispatching chambers, a hot rivet

receiving opening in the top of the dispatching chamber, a counterbalanced upwardly seating pivoted valve normally closing the rivet receiving opening, the aforesaid conduit being disposed below and outwardly inclined relative to the receiving opening, a vertically movable headed rod slidably connecting with the aforesaid spring influenced valve and having pivotal connection with a foot lever fulcrumed below the transverse partition whereby said valve is opened to impel the hot rivet through the aforesaid conduit, and an adjustable stop for regulating the movement of the foot lever to vary the opening of the spring influenced valve as desired. 20 25 30 35

In testimony whereof I affix my signature.

WILLIAM F. WRIGHT.
